UNITED STATES PATENT OFFICE.

EDWIN W. KELLY, OF PHILADELPHIA, PENNSYLVANIA.

ANTICATHODE.

1,254,700.

Specification of Letters Patent. Patented Jan. 29, 1918.

Application filed September 30, 1916. Serial No. 122,960.

To all whom it may concern:

Be it known that I, EDWIN W. KELLY, a citizen of the United States, residing in the city and county of Philadelphia, State of Pennsylvania, have invented certain new and useful Improvements in Anticathodes, of which the following is a specification.

My invention relates to improvements in anti-cathodes and the like for electric vacuum tubes, and particularly anti-cathodes employed in X-ray tubes.

In the production of X-rays there are employed within a highly evacuated tube or bulb a cathode, connected to the negative terminal of a source of high tension unidirectional current, and an anti-cathode, which may be also the anode connected to the positive terminal of the source of current. A bombardment of the anti-cathode by a so-called "cathode-stream" is induced by the electric pressure, and such bombardment is accompanied by wasteful evolution of heat and the generation of useful X-rays.

As the X-ray art has advanced, progressively greater amounts of electric energy have been passed through the X-ray tube with increasing intensities of the aforementioned bombardment, necessitating from time to time improvements in the anti-cathode structure.

It is the object of my invention to further improve anti-cathodes and to such end I provide an anti-cathode which is at once simple in structure, which shall withstand bombardment at even higher intensities than heretofore, which shall withstand bombardments for longer periods, which shall not so readily allow vaporization of metal which causes a change in the degree of vacuum in the tube, which shall allow immediate energization of the tube at full rate without preliminary warming by reduced excitation or otherwise, and which shall materially reduce tendency to or prevent cracking of the refractory material of the anti-cathode, my invention residing in an anti-cathode having some or all of these characteristics.

For an illustration of some of the forms my invention may take reference is to be had to the accompanying drawing, in which:

Figure 1 represents in a simple way an X-ray tube.

Fig. 2 is a side elevational view of an anti-cathode embodying my invention.

Fig. 3 is a longitudinal sectional view

through an anti-cathode in modified form embodying my invention.

Referring to Fig. 1, X is an X-ray tube or bulb having integral therewith the cathode stem a within which is disposed the cathode C electrically connected with the exterior terminal b which may be connected to the negative terminal of a source of high potential current. The tube X has also a second stem c within which is a support d on which is carried the anti-cathode A, which in this case may also be the anode having the exterior terminal e which may be connected with the positive terminal of the source of high potential current.

In the operation of an X-ray tube the cathode stream bombards the refractory metal T, which may be tungsten or other suitable material, and the bombardment is accompanied by an evolution of heat at the member T and the production of X-rays which pass through the walls of the tube X. The heat generated at the member T is absorbed by the head H and from it gradually dissipated by radiation and conduction.

In the past it has been common to use for the head or heat absorbing and storing member as H a mass of metal of good heat conductivity, generally and almost exclusively of copper, and such anti-cathodes have served well their purpose when considering the conditions which led to their introduction.

But I have found that by recourse to the materials and structures hereinafter described an anti-cathode is available which has desirable qualities and characteristics amounting to substantial advantages over prior structures and overcoming their limitations.

Referring now to Fig. 2, the anti-cathode A comprises the cylindrical or otherwise shaped mass H of iron, nickel, iron-nickel alloy, or other suitable material of similar characteristics. To its front face, usually at an angle of 45 degrees with its longitudinal axis, is attached the refractory element T which may be of tungsten or any other suitable refractory material. It is welded or similarly attached throughout the extent of its entire or substantially entire back face f to the head H, and the union between the members T and H forms a perfect or direct thermal contact.

The thickness of the member T may be

less or greater than that indicated in the drawing, and the members H and T may partake of other shapes and dimensions than those indicated.

5 In Fig. 3 the anti-cathode A¹ is similar to that shown in Fig. 2, with the exception that the refractory member T is set into the head H, but is nevertheless welded or otherwise similarly attached so that its back face f, 10 and if desired also its peripheral face g, is in direct or perfect thermal contact with the head H.

While copper has high or good heat conductivity, .72, iron and nickel are poor conductors of heat, their heat conductivities being respectively .158 (Landoldt and Börnstein) and .142 (Landoldt and Börnstein), from which it is seen that copper has a heat conductivity from 4.5 to 5 times 20 that of iron or nickel.

I take advantage of this poor heat conductivity of the head H to prevent, notwithstanding the perfect or direct thermal contact between them, rapid heat transfer 25 from the refractory element T. Because of the poor heat conductivity of the member H the front or bombardment receiving face i of the refractory member T and its back face f will be maintained at more nearly 30 equal temperatures because the member H does not quickly absorb heat from the member T. This greater approximation to equality of temperature throughout the member T minimizes the difference in expansion 35 at its front and rear faces and therefore reduces the internal strains within the member T which otherwise may cause it to crack or which may cause other disadvantageous effect.

40 Furthermore, the co-efficients of linear expansion, per degree centigrade, for iron and nickel are materially less than that of copper, being respectively .00001092 (Landoldt and Börnstein) and .00001012 (Landoldt and Börnstein), while that of copper is .0000149 (Landoldt and Börnstein). On the other hand the co-efficient of linear expansion of tungsten is .00000336 (Coolidge). From this it is apparent that by the use of 50 nickel or iron or other material of lower co-efficient of linear expansion than copper, when the element T is of tungsten or other material of low co-efficient of linear expansion, the difference in expansion between the 55 element T and the head H is reduced, with a further reduction of the strains imposed upon the member T, and so further reducing the liability of cracking or other effect.

An alloy comprising 31.4% nickel and 60 68.6% iron has a very small co-efficient of linear expansion, namely .0000034 (Kent), which is very closely that of tungsten, with the result that a head H of such alloy or similar alloy will differ so slightly in co- 65 efficient of linear expansion that the strains

imposed upon the tungsten member T due to such difference is practically negligible.

Furthermore, the employment for the head H of iron or nickel or other material of high specific heat as compared to copper 70 affords, for equal masses, a relatively greater heat storage capacity thereby permitting, for a given rise in temperature of the head H, a longer or more violent excitation of the X-ray tube. 75

Iron and nickel both melt at higher temperatures than copper, and from this flows the additional advantage that under intense excitation neither the iron nor nickel will vaporize as quickly as copper, and the prevention of vaporization implies the prevention of irregular uncontrollable changes in degree of vacuum of the X-ray tube. 80

While I have hereinbefore stated that iron, nickel or an alloy of them, may be used 85 for the head H, it will be understood that other metals or alloys may be employed when they have one or more of the advantageous characteristics herein pointed out.

By the use of a backing H of the characteristics herein described it is possible immediately and without any preliminary passage of energy of lower quantity for gradual heating purposes to apply to an X-ray tube at ordinary or room temperatures 90 the full amount of energy intended or required for its operation. This immediate application of the full amount of energy is accompanied with no detrimental effects such as are observable when the member H 100 is of copper. This advantage in favor of iron, nickel or other material of the character herein referred to is believed to be largely due to the fact that the temperature gradient between the front face i and the 105 rear face f of the member T is small because of the poor heat conductivity of the member H.

While the smaller co-efficient of linear expansion, the higher specific heat and the 110 lower heat conductivity of member H are each individually of advantage in the directions indicated, these characteristics also mutually contribute to an improvement of the behavior of the anti-cathode particularly in that, while not subject to effects hereinbefore described, a given amount of energy may be passed through the X-ray tube for a longer time and greater amounts of energy may be passed through the X-ray 115 tube than in the case of the anti-cathodes herein referred to having heads H of copper. 120

It will be understood that the term "iron" as herein employed includes steel and alloy steels. 125

What I claim is:

1. An anti-cathode comprising a head of metal of poor heat conductivity and a member of refractory metal welded directly thereto. 130

2. An anti-cathode comprising a mass of metal comprising iron, and a refractory metal member set into said mass and welded directly thereto.
3. An anti-cathode comprising a mass of alloy, and a refractory member in direct thermal contact with said mass and having a co-efficient of expansion approximately equal to the co-efficient of expansion of said alloy.
4. An anti-cathode comprising a mass of metal comprising iron, and a refractory member of metal welded directly to said mass.
- 15 5. An anti-cathode comprising a mass of iron alloy, and a refractory member welded directly thereto.
6. An anti-cathode comprising a mass of metal comprising iron and nickel, and a refractory member welded directly thereto.
- 20 7. An anti-cathode comprising a mass of metal comprising iron and nickel, and a member of tungsten welded directly thereto.
8. An anti-cathode comprising a mass of 25 iron and nickel alloy having a co-efficient of linear expansion approximately equal to that of tungsten, and a member of tungsten in heat conductive relation therewith.
9. An anti-cathode having a head comprising iron, and a member of tungsten welded directly thereto.
10. An anti-cathode comprising a head of metal having a heat conductivity materially less than and a specific heat greater than copper, and a member of refractory material welded directly thereto.
11. An anti-cathode comprising a head of metal having a co-efficient of linear expansion less than and a heat conductivity materially less than copper, and a member of refractory material welded directly thereto.
12. An anti-cathode comprising a head of metal having a heat conductivity materially less than copper and a melting-point higher than copper, and a member of refractory material welded directly thereto.

In testimony whereof I have hereunto affixed my signature this 28 day of Sept., 1916.

EDWIN W. KELLY.
